UNITED STATES PATENT OFFICE.

CUTHBERT GENTLE, OF DORCHESTER, MASSACHUSETTS, ASSIGNOR TO THOMAS H. BOWDIDGE, OF BOSTON, MASSACHUSETTS.

DESIGN FOR A BEVERAGE-HEATER.

43,958.

Specification for Design.

Patented May 6, 1913.

Application filed February 26, 1913. Serial No. 750,884. Term of patent 7 years.

To all whom it may concern:

Be it known that I, CUTHBERT GENTLE, a subject of the King of England, residing at Dorchester, in the county of Suffolk and State of Massachusetts, have invented a new, original, and ornamental Design for Beverage-Heaters, of which the following is a specification, reference being had to the accompanying drawing, forming part thereof.

The figure is a perspective of a beverage heater, showing my new design.

I claim:

The ornamental design for a beverage heater, as shown.

CUTHBERT GENTLE.

Witnesses:

BION B. LIBBY,
GRACE A. DEVER.
